STEREO-TAPE PLAYER

Robert P. Maniaci, Downey, Calif., assignor to California
Auto Radio Inc., Downey, Calif.

Filed Mar. 31, 1970, Ser. No. 22,145

Term of patent 14 years

Int. Cl. D14—02

U.S. Cl. D26—14

FIG. 1 is a front perspective view of a stereo tape player wherein the back is conventionally plain; and

FIG. 2 is a side elevation thereof, the undisclosed opposite side being a mirror image of the side shown.

I claim:

The ornamental design for a stereo-tape player, substantially as shown and described.
